GROUND ROD PULLER

Howard Leroy Hill, Taft, Calif.

Application June 6, 1940, Serial No. 339,183

1 Claim. (Cl. 254—31)

The present invention relates to new and useful improvements in means for pulling metal rods such as are used for grounding electric circuits and has for its primary object to provide, in a manner as hereinafter set forth, a device whereby these rods may be expeditiously extracted with a minimum of effort.

Another very important object of the invention is to provide a puller of the aforementioned character embodying novel means for firmly gripping the ground rod to be extracted.

Still another very important object of the invention is to provide a ground rod puller of the character described comprising a construction and arrangement which is such that the device may be conveniently assembled and disassembled thereby greatly facilitating maintaining the device in proper working order.

Other objects of the invention are to provide an electric ground rod puller which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a ground rod puller constructed in accordance with the present invention.

Figure 2 is a top plan view of the device.

Figure 3 is a vertical sectional view, taken substantially on the line 3—3 of Fig. 1.

Figure 4 is a vertical sectional view, taken substantially on the line 4—4 of Fig. 2.

Figure 5 is a view in horizontal section, taken substantially on the line 5—5 of Fig. 1.

Figure 6 is a top plan view of the slips.

Referring now to the drawings in detail, it will be seen that the embodiment of the invention which has been illustrated comprises a substantially rectangular base 1 of suitable metal. Rising from the base 1 is a cylinder 2 which is open at its upper end. A brace 3 is provided for the cylinder 2. An opening 4 in the base 1, which accommodates the rod to be extracted, communicates with the cylinder 2.

Extending outwardly and upwardly from an upper portion of the cylinder 2 is a bifurcated bracket 5. Pivotally mounted between the bifurcations of the bracket 5 for swinging movement

in a vertical plane, through the medium of a pin or the like 6, is a lever 7. On the rear end of the lever 7 is a socket 8 for the reception of one end portion of a removable operating handle 9. On the forward end of the lever 7 is a fork 10.

Mounted for reciprocation in the cylinder 2 is a piston which is designated generally by the reference numeral 11. The piston 11 comprises a reduced head 12 having formed therein a centrally located opening 13. The head 12 is further provided, in its side portions, with parallel grooves or channels 14 (see Fig. 5). The grooves or channels 14 accommodate the reduced lower end portions 15 of a pair of connecting rods 16 which are pivotally secured therein by bolts 17. At their upper ends, the connecting rods 16 terminate in bifurcations 18 which straddle the arms of the fork 10 and which are pivotally connected thereto by bolts 19. Thus, the piston 11 is connected to the lever 7 for actuation thereby.

The piston 11 still further includes an internally threaded skirt 20. Threadedly mounted in the skirt 20 and depending therefrom for reciprocation in the cylinder 2 with the piston 11 is an internally tapered slip socket 21. The reference numeral 22 designates a pair of externally tapered slips which are mounted in the socket 21. The rod engaging faces of the coating slips 22 are roughened or toothed, as at 23. The slips 22 further include substantially conical lower portions 24 to facilitate the introduction of the rod therebetween.

It is thought that the manner of using the device will be readily apparent from a consideration of the foregoing. Briefly, the device is placed in working position over the ground rod to be extracted, said rod passing upwardly through the opening 4 between the slips 22 which constitute gripping jaws. The opening 13 permits a portion of the rod to pass upwardly through the piston 11. Now, when the handle 9 is swung downwardly the piston 11 with the socket 21 are elevated in the cylinder 2. Thus, the slips 22 firmly grip the rod in an obvious manner for extracting same. Of course, the longer the lever 9, the greater the leverage that may be had for removing the rod. If desired, a new hold or grip may be had on the rod by simply swinging the handle 9 upwardly. It will be observed that the construction and arrangement is such that the piston 11 with the slip socket 21 thereon may be conveniently removed from the cylinder 2 for repairing or replacing any of the parts.

It is believed that the many advantages of an electric ground rod puller constructed in ac-

cordance with the present invention will be readily understood and although a preferred embodiment of the device is as illustrated and described, it is to be understood that changes in the details 5 of construction and in the combination and arrangement of parts may be resorted to which will fall within the scope of the invention as claimed.

What is claimed is:

A ground rod puller of the character described 10 comprising a base, a cylinder rising from the base, said base having an opening therein communicating with the cylinder for the passage of a rod to be extracted, a bracket on the cylinder, a lever pivotally mounted on said bracket, a socket 15 member on one end of the lever for the reception

of a handle, a fork on the other end of said lever, a piston slidable in the cylinder and including a reduced head having an opening therein for accommodating the rod, the reduced head further having parallel channels therein, a pair of connecting rods having one end pivotally connected to the fork and their other ends pivotally secured in the channels, the piston further including an internally threaded skirt, a removable, internally tapered socket threadedly connected to the skirt, and a plurality of slips operatively mounted in said socket and adapted to grip the rod. 5 10
